United States Patent Office.

JAMES G. LUCAS, OF NEWARK, NEW JERSEY, ASSIGNOR TO HIMSELF AND
ARETUS L. SAWIN.

Letters Patent No. 78,983, dated June 16, 1868; antedated June 4, 1868.

IMPROVEMENT IN MACHINE FOR BENDING WOOD.

The Schedule referred to in these Letters Patent and making part of the same.

TO ALL WHOM IT MAY CONCERN:

Be it known that I, JAMES G. LUCAS, of Newark, in the county of Essex, and State of New Jersey, have invented certain new and useful Improvements in Presses for Shaping Trunk-Tops; and I do hereby declare that the following is a full, clear, and exact description of the same, reference being had to the accompanying drawings, making a portion of this specification, in which—

Figure 1 is a central vertical longitudinal section of a press constructed according to my invention.

Figure 2 is a central vertical transverse section of the same.

Similar letters of reference indicate corresponding parts in both figures.

In making the bulged tops of trunks, much difficulty has been experienced in securing such curvature of the different parts of the surface as will give the requisite symmetry to the same, and the object of this invention is to provide a machine by which the result mentioned may be secured, and which, furthermore, may be employed for pressing or shaping tops of any desired size.

The invention consists in a longitudinally-recessed former so combined with a presser-die that the central parts of the trunk-top may be confined and pressed into the flattened form required in the finished tops. The invention also consists in the combination of side presser-stays with the just-mentioned former, whereby the lateral portions of the tops are brought upon the surface of the former, and made to conform in shape thereto.

To enable others to understand the construction and operation of my invention, I will proceed to describe it with reference to the drawings.

The supporting-frame of the press is shown at A. Each of the four corner posts thereof is extended upward, with the two at each end connected at the top by a cross-bar, a. The side-rails b of this frame are divided centrally, as shown at a* in fig. 1, each portion of each rail being formed with an oblong vertical slat. Placed upon the divided side-rails just mentioned, are horizontal bars, e, each of which has at each end a vertical screw, b*, passing down through the slat in the adjacent part of the side-rail, and provided below the said rail with a nut, a'. By placing the screws b* at suitable points in the slats aforesaid, the frame A may be lengthened or shortened to adapt the press for working upon tops of different lengths, as hereinafter set forth.

At each end of the frame A, working in bearings provided upon the upright corner-posts, and situated, one at the upper and the other at the lower part of the said posts, are horizontal rods d, furnished at one end with pulleys, c*, connected by a band, d*, in such manner that one of the said rods being rotated by a crank, b', a corresponding movement will be communicated to the other. Each of the aforesaid rods is formed with a screw-thread at each end, the two threads or screws of each rod running in opposite directions, and passing through the adjacent ends of vertical clamping-bars f, in such manner that, by turning the rods, as just set forth, in one direction or the other, the aforesaid clamping-bars upon each pair of rods d will be made to approach or recede from each other, as the case may be, the said bars serving to clamp the frame B, hereinafter described, in place, as indicated in fig. 2.

Resting upon the horizontal end-pieces f* of the supporting-frame A is a horizontal rectangular frame, B, the side-pieces, g, of which are hollowed or made concave at their inner sides to correspond to the lateral portions of the "former," hereinafter described, and which constitute the side presser-stays of the press. Secured centrally to the under side of the frame B is a transverse brace, m, fixed centrally upon the upper side of which is a presser-die, C, which, taken longitudinally, is depressed or hollowed out at its upper side, as shown in fig. 1, but which, in its transverse section, is arched, as represented in fig. 2.

D represents a block or "former," the under side of which is so shaped as to correspond with the curved or bulged surface of the finished trunk-top, except that it has formed in it a longitudinal recess or depression, as shown at g*. E indicates horizontal bars, of which there is one at each end of the supporting-frame A, the extremities of the said bars working in vertical guides provided upon the posts of the aforesaid supporting-frame. The bars E are pressed downward in the operation of the press by screws F working through the

cross-bars *a*, and furnished at their upper ends with cranks or hand-wheels *n*, as shown in the drawings, whereby they may be conveniently turned. When preferred, the former *D* may be attached in any suitable manner to the lower ends of the screws *F*, so as to be lifted as well as depressed by the operation of the said screws.

In using the press, the boards from which it is designed to form the trunk-top, having been duly prepared for bending or shaping by steaming and soaking, or other means, are placed upon the frame *B*, as shown in red outline in the drawings, it being intended that each trunk-top be formed of two boards laid side by side, as shown more fully in fig. 2, any desired number of thicknesses of boards being laid one upon another, which being done, the former *D* is placed upon the boards and pressed downwards by means of the screws *F*, the boards being compressed between the side presser-stays, and the lateral portions of the said boards are made to conform in shape to the said parts of the former at the same time that the presser-die *C*, by forcing the central portions of the boards upward toward and to some extent into the longitudinal recess *g** of the aforesaid former, causes such central portions of the boards to assume such a shape that, when the two boards of which a top is formed are properly fitted together, the central part of such top will have the flattened contour required to insure a symmetrical appearance of the trunk. It will be borne in mind that the boards, resting with their ends upon the end-piece of the frame *B*, are caused by the said end-piece to follow or be pressed upon the longitudinal curvature of the former *D*, the office of the side presser-stays being to press the boards upon the lateral portions of the said former, so that, by the means described, the end and lateral edges of the trunk-top may both be made depressed at the same time that the requisite flatness of the central part of the trunk-top is secured.

Different sizes of trunk-tops may be shaped by employing frames *B* and formers *D* of corresponding size, the clamping-bars *f* being adjusted to suit the width of the frame, and the length of the supporting-frame *A* being increased or diminished, as hereinbefore set forth, to suit the length thereof. To prevent the lowermost boards from dragging upon the side presser-stays *g* during the shaping or pressing operation, it is preferred to insert friction-rollers longitudinally and at suitable distance apart in those surfaces of the side presser-stays which force the boards against or towards the former.

What I claim as my invention, and desire to secure by Letters Patent, is—

1. The longitudinally-recessed former, in combination with the presser-die constructed to operate substantially as and for the purpose specified.
2. The side presser-stays, in combination with the former, constructed to operate substantially as and for the purpose specified.

JAMES G. LUCAS.
